UNITED STATES PATENT OFFICE

149,851

DESIGN FOR A SWEATER

Berté A. Wiechmann and Fay W. Robson, Portland, Oreg., assignors to Jantzen Knitting Mills, a corporation of Oregon

Application March 7, 1947, Serial No. 137,454

Term of patent 3½ years

(Cl. D3—4)

To all whom it may concern:

Be it known that we, Berté A. Wiechmann and Fay W. Robson, citizens of the United States, residing at Portland, in the county of Multnomah, State of Oregon, have invented a new, original, and ornamental Design for a Sweater, of which the following is a specification, reference being had to the accompanying drawing, forming a part thereof.

In the drawing:

Fig. 1 is a front view of a sweater showing our new design, and Fig. 2 is a rear view thereof.

We claim:

The ornamental design for a sweater, substantially as shown.

BERTÉ A. WIECHMANN.
FAY W. ROBSON.
